(57) **CLAIM**

We claim the ornamental design for an intercom beltpack, as shown and described.

DESCRIPTION

FIG. 1 is a first perspective view of an intercom beltpack showing our new design;

FIG. 2 is a second perspective view thereof;

FIG. 3 is a right side elevation view thereof;

FIG. 4 is a left side elevation view thereof;

FIG. 5 is a front elevation view thereof;

FIG. 6 is a rear elevation view thereof;

FIG. 7 is a top plan view thereof; and,

FIG. 8 is a bottom plan view thereof.

The broken lines are for the purpose of illustrating portions of the intercom beltpack that form no part of the claimed design.
